TWO-DIRECTION MOVEMENT REGULATOR

Alfred S. Greif, Detroit, Mich., assignor to
Ternstedt Manufacturing Company, Detroit,
Mich., a corporation of Michigan

Application April 17, 1939, Serial No. 268,173

5 Claims. (Cl. 268—126)

This invention relates particularly to window regulators for use in "Fisher No Draft" ventilating windows. The "Fisher No Draft" ventilating system is described and claimed in the Fisher Patent No. 2,048,605. In these ventilating systems, it is customary to use either a fixed division pillar which remains in position regardless of the position of the panels, or else to use a stile or channel on the sliding panel which slides up and down with the sliding panel. In the Fisher patent, an H channel is disclosed and the division line between the two panels inclines rearwardly from bottom to top. Hence, when the sliding panel is first lowered, the stile withdraws from engagement with the front swinging panel. This arrangement is shown and claimed in the Simpson Patent No. 2,087,821. Another arrangement which is quite extensively used utilizes a vertical stile on the sliding panel but of H cross section. When the sliding panel is lowered, the weather-strip on the stile rubs the edge of the swinging panel all the way down and is open to the objection that it wears the strip and also, in a measure, interferes with the lowering operation. It is the purpose of the invention about to be described to overcome these difficulties and yet utilize a vertically disposed stile. This is accomplished by an arrangement whereby the regulator at the beginning of the lowering operation causes the sliding panel to move a slight distance to the rear to separate the two panels and then the regulator operates to lower the sliding panel.

In the drawings:

Fig. 1 is an elevation of the window regulator in connection with fragmentary parts of the two panels showing the panels in their fully closed position.

Fig. 2 is a similar view showing the panels after they have been separated by a horizontal movement of the sliding panel.

Figs. 3 and 4 are sections on the corresponding section lines of Fig. 1.

Figs. 5, 6 and 7 are sections taken on the corresponding section lines of Fig. 2.

Fig. 8 is a section taken on the line 8—8 of Fig. 1.

Fig. 9 is a section taken on the section line 9—9 of Fig. 2.

Figs. 10 and 11 are details showing the two positions of the major and minor sectors.

1 designates the swinging panel of the "Fisher No Draft" ventilator, 2 the sliding panel. However, this sliding panel is capable of a small horizontal movement as well as a vertical movement.

This movement can be observed by comparing the position of the two panels in Figs. 1 and 2.

The window regulator comprises a sector type of regulator of a common type. This includes a clutch, not shown, but contained in clutch case 3, 5 a driving pinion 4 which has teeth that mesh with the usual toothed sector 5.

This sector has the usual lifting arm 6. This lifting arm is preferably provided with an additional arm 7, the lower end of which travels in the horizontal guide 8 and the upper end has a roll that travels in the horizontal guideway 9 on the bottom of the sliding sash 2. This is an improvement described and claimed in Graf Patent No. 2,010,075.

The sliding panel 2 is provided with an H section channel 10. This is a vertically disposed channel and, when the panels are closed, this channel straddles the rear edge of the swinging panel and locks the two together so as to make 20 a near air-tight seal and, at the same time, prevents one prying the swinging panel open to get into the car from the outside.

My improvement consists of an arrangement whereby the sliding panel in the initial lowering 25 operation moves first rearwardly from the position shown in Fig. 1 to the position shown in Fig. 2. This is accomplished by a slight relative movement between the minor sector 11 and the major toothed sector 5.

Referring to Figs. 10 and 11, it will be seen in Fig. 10 that a tooth 12 on the minor sector is engaged between two teeth on the driving pinion 4. When the driving pinion is turned clockwise, the minor sector 11 will move a short distance counter-clockwise until the lip 13 on the minor sector moves from the position shown in Fig. 10 to that shown in Fig. 11. In this latter position, the lip strikes the edge 14 of the major sector 5. The pin 15 on the minor sector engages in a notch 16 in the arm 17. This arm 17 has a hooked end 18 provided with a notch 19 that engages the pin 20 on the bracket 21 attached to the bottom of the sliding panel. When the driving pinion is first turned counter-clockwise in Fig. 1, it first rotates the minor segment 11 clockwise. The pin 15, engaging in notch 16, pushes arm 17 to the right and arm 17, with its notch 19 engaging over pin 20, pushes the sliding window rearwardly from the position shown in Fig. 1 to the position shown in Fig. 2, thereby separating the two panels a slight distance. This distance is shown by comparing Figs. 1 and 2 and Figs. 8 and 9.

The sliding arm 17 has slots 22 and 23 through which pins 24 and 25, attached to the window 55

regulator plate 26, engage so as to guide the arm in its sliding movement. When the pin 15 has passed from the position shown in Fig. 1 to that shown in Fig. 2, it reaches the mouth of the slot 5 16 and the flared opening 27 of the slot now permits the pin to clear the arm 17 as it moves upwardly in an arc whose center is the pivot point 28 of the major sector 5 after the two sectors come together and move as a unit when the lip 10 13 engages the edge 14 of the major sector. The two sectors are held together on the fulcrum pin 29. A torsion spring 30 biases the minor sector and tends to bring the lip 13 in contact with the edge 14 of the major sector.

15 In order to hold the major segment in a determined position when the sliding panel is in its uppermost position, a latch 31 spring-pressed by spring 32 and pivoted on the window regulator plate 26 is provided. On Figs. 1 and 2, the latch 20 is seen contacting with the upper edge of the major sector 5. As the small sector 11 makes its limited relative movement with respect to the large sector, the struck out cam lip 33 cams this latch out of the way as will be seen by comparing 25 Figs. 4 and 5. The major sector 5 is now free to move past the latch. This latch serves to hold the major sector in a definite position so that, at a given point in the lifting or descent, the relative movement can take place between the 30 two sectors. This cam lip 33 engages in a notch 34 in the major sector 5 so that, when the two sectors start to move together (as shown in Fig. 5), the cam lip 33 has cammed the latch 31 out of position so that the upper edge 14 of the major 35 sector may now pass the latch 31. On return movement, as soon as the upper edge of the large sector passes the latch, the latch drops behind this edge, as shown in Fig. 4.

It is not broadly new to provide a window regulator in connection with the "Fisher No Draft" 40 ventilating system which will first separate the panels by a movement of the sliding panel horizontally and then moving the sliding panel downwardly. A regulator of this type is shown and broadly claimed in the Kegler Patent No. 2,152,- 45 055. Nor is the use of my regulator necessarily confined to a ventilating system, such as the "Fisher No Draft" for the regulator per se is useful wherever a window panel has to first move horizontally and then downwardly and vice-versa.

What I claim is:

1. In a window regulator for a sliding panel which in its initial movement to open the window 55 moves first rearwardly a slight distance and then downwardly, the combination of a major toothed sector provided with lifting means for lifting and lowering the sliding window, a minor toothed segment pivoted to the major segment and arranged 60 to have a limited relative movement with respect thereto, an operating connection between the minor toothed segment and the window for moving the window rearwardly and forwardly when relative movement between the minor sector and the major sector takes place and a driving pinion 65 engaging the teeth of the minor and major sectors and arranged when the window reaches its topmost position to leave the teeth of the major sector and operate only on the teeth of the minor sector to cause forward movement of the window panel and conversely when the opening movement 70 of the panel takes place to move the minor sector a limited distance independently of the major sector to slide the window rearwardly and then

to pick up the teeth of the major sector to move the window downwardly.

2. In a window regulator for a sliding panel which in its initial movement to open the window moves first rearwardly a slight distance and then downwardly, the combination of a major toothed sector provided with lifting means for lifting and lowering the sliding window, a minor toothed segment pivoted to the major segment and arranged to have a limited relative movement with respect thereto, an operating connection between the minor toothed segment and the window for moving the window rearwardly and forwardly when relative movement between the minor sector and the major sector takes place, a driving pinion engaging the teeth of the minor and major sectors and arranged when the window reaches its topmost position to leave the teeth of the major sector and operate only on the teeth of the minor sector to cause forward movement of the window panel and conversely when the opening movement of the panel takes place to move the minor sector a limited distance independently of the major sector to slide the window rearwardly and then to pick up the teeth of the major sector to move the window downwardly, and a latch arranged to engage the major sector when the panel is in its uppermost position to hold the major segment from further movement while an independent movement of the minor segment takes place.

3. In a window regulator for a sliding panel which in its initial movement to open the window moves first rearwardly a slight distance and then downwardly, the combination of a major toothed sector provided with lifting means for lifting and lowering the sliding window, a minor toothed segment pivoted to the major segment and arranged to have a limited relative movement with respect thereto, an operating connection between the minor toothed segment and the window for moving the window rearwardly and forwardly when relative movement between the minor sector and the major sector takes place, a driving pinion engaging the teeth of the minor and major sectors and arranged when the window reaches its topmost position to leave the teeth of the major sector and operate only on the teeth of the minor sector to cause forward movement of the window panel and conversely when the opening movement of the panel takes place to move the minor sector a limited distance independently of the major sector to slide the window rearwardly and then to pick up the teeth of the major sector to move the window downwardly, a latch arranged to engage the major segment when the panel is in its uppermost position to hold the major segment for a further movement while an independent movement of the minor segment takes place, and a cam on the minor segment operating on said latch on the initial movement of the minor segment independently of the major segment to release the latch to permit the major segment to move past the latch.

4. In a window regulator for a sliding panel which in its initial movement to open the window moves first rearwardly a slight distance and then downwardly, the combination of a major toothed sector provided with lifting means for lifting and lowering the sliding window, a minor toothed segment pivoted to the major segment and arranged to have a limited relative movement with respect thereto, an operating connection between the minor toothed segment and the window for moving the window rearwardly and forwardly

when relative movement between the minor sector and the major sector takes place, and a driving pinion engaging the teeth of the minor and major sectors and arranged when the window reaches its topmost position to leave the teeth of the major sector and operate only on the teeth of the minor sector to cause forward movement of the window panel and conversely when the opening movement of the panel takes place to move the minor sector a limited distance independently of the major sector to slide the window rearwardly and then to pick up the teeth of the major sector to move the window downwardly, the said operating connection with the panel comprising an arm guided for forward and rearward movement having a connection releasable with the sliding panel by vertical movement of such panel, said arm automatically releasing from its connection with the minor sector upon a limited relative movement between the sectors.

5. In a window regulator for a sliding panel which in its initial movement to open the window moves first rearwardly a slight distance and then downwardly, the combination of a major toothed sector provided with lifting means for lifting and lowering the sliding window, a minor toothed segment pivoted to the major segment and arranged to have a limited relative move-

ment with respect thereto, an operating connection between the minor toothed segment and the window for moving the window rearwardly and forwardly when relative movement between the minor sector and the major sector takes place and a driving pinion engaging the teeth of the minor and major sectors and arranged when the window reaches its topmost position to leave the teeth of the major sector and operate only on the teeth of the minor sector to cause forward movement of the window panel and conversely when the opening movement of the panel takes place to move the minor sector a limited distance independently of the major sector to slide the window rearwardly and then to pick up the teeth of the major sector to move the window downwardly, the said operating connection with the panel comprising an arm guided for forward and rearward movement having a connection releasable with the sliding panel by vertical movement of such panel, said arm automatically releasing from its connection with the minor sector upon a limited relative movement between the sectors, a flared notch and pin connection between the minor sector and the arm achieving this release and a reconnection of the parts.

ALFRED S. GREIF.
